United States Patent Office.

W. B. BARTRAM, OF DANBURY, CONNECTICUT.

Design No. 3,478, dated May 11, 1869.

DESIGN FOR THE FRAME OF A SEWING-MACHINE.

The Schedule referred to in these Letters Patent and making part of the same.

To all whom it may concern:

Be it known that I, W. B. BARTRAM, of Danbury, in the county of Fairfield, and State of Connecticut, have invented a new Design for Frame, &c., of a Sewing-Machine; and I do hereby declare the following to be a full, clear, and exact description of the same, reference being had to the accompanying drawings, in which the figure represents a side elevation of my machine.

The frame A presents the form and appearance of a tapered bar, bent in the manner shown; that is to say, the larger end of said bar is joined to the convex disk B, which forms the base of the machine. From this base, said bar is curved upward in an arc of a circle, until a point is reached about vertical to the side of the disk from which the bar A takes its rise.

From this point the bar is straight and horizontal until a point is reached from which a plummet would fall outside of the disk, and the bar then resumes its curved form in an arc of the same circle before described.

The frame A terminates at a point which would mark the completion of about two-thirds of a circle from place of commencement on the disk B; and the general figure is that of a circle flattened.

The guide-head C is supported at the outer or smaller end of the frame A, and the sewing-table D

is supported upon the arm E, whose curve is convex to the curve of the bar A, *i. e.*, it is curved about a centre, which is located outside of the periphery of the frame-bar A.

The driving-shaft F passes across the frame A, and has its bearings at one end upon said frame, and at the other end in the head of the arm E, and the tension-case is located upon the side of bar A, above the bearing of the driving-shaft.

The driving-pulley G is located upon the end of the driving-shaft outside of the frame of the machine.

The driving-shaft presents a straight line across the lower part of the frame, and the straight line of the flattened circle at the top of the frame is its foil.

The tension and driving-pulley presents a mass at one side, which is balanced by the guide-head and sewing-table upon the other side, so that the whole presents an arrangement of parts pleasing to the eye and convenient in use.

Having described my design,
What I claim, is—

The design for the frame of a sewing-machine herein set forth.

W. B. BARTRAM.
